UNITED STATES PATENT OFFICE.

TULLY DE STEFANI, OF CHICAGO, ILLINOIS, ASSIGNOR TO LIQUID CARBONIC COMPANY, OF CHICAGO, ILLINOIS, A CORPORATION OF ILLINOIS.

COOLER CABINET FOR SODA FOUNTAINS.

Application filed March 2, 1922. Serial No. 540,636.

This invention relates to improvements in the ice cream cabinets or receptacles of soda fountains and particularly to improvements in the covers and lids of such receptacles.

5 The principal object of the invention is to provide an ice cream or other receptacle having an improved cover. Another object is to provide a cover having an improved detachable lid. Still another object is to provide a 10 cover having a circular aperture therethrough adapted to be closed by a circular lid, in combination with an improved hinged mounting for the lid. A further feature is the provision of a cover having a removable lid, in 15 combination with an improved hinge mounted on the inner sides of the cover and lid. Other objects relate to other features of construction and arrangement which will appear more fully hereinafter.

20 The nature of the invention will be understood from the following specification taken with the accompanying drawings in which one embodiment is illustrated. In the drawings,

25 Fig. 1 shows a vertical section through the cooling box of a soda fountain embodying the improvements of the present invention, the section being taken at right angles to the longitudinal axis of the fountain;

30 Fig. 2 shows a detail section taken on the line 2—2 of Fig. 1 looking in the direction of the arrows;

Fig. 3 shows a bottom plan view of the cover and lid, and

35 Fig. 4 shows a perspective view of the bracket by which the hinge is connected to the under side of the cover.

The invention is illustrated in connection with the cooling box 10 of a soda fountain

40 which comprises an ice cream receptacle 11 having an interior lining 12 of tinned copper or the like, surrounded by a layer 13 of cork or other heat insulating material. The top of the cooler box is formed by a capping

45 14 of nickel silver or other suitable material which is bent upwardly along the inner edge of the box to form a ridge 15 and thence extending downwardly along the side of the box as shown at 16. The lining 12 which is

50 cylindrical in form terminates below the metal capping 14 as shown at 17, and the capping is provided with an annular downwardly extending flange 18 located inwardly from the lining 12. An annular band 19 of heat insulating fiber is mounted between the

flange 18 and the lining 12 so that the passage of heat from the capping 14 to the lining of the ice cream receptacle is prevented. These features constitute an improvement which is described and claimed in my copending application, Ser. No. 540,635 filed March 2, 1922.

The ice cream receptacle is provided with a cover 20 which is formed by two sheets 21 and 22 of nickel silver or the like which are die stamped into the form shown and inter-fitted and united with each other without the use of rivets or other similar fastening means. The space between the two sheets of metal is filled by cork 23 or other heat insulating material. The outer annular edge of the lower plate 22 is inclined outwardly and upwardly as shown at 25 adjacent the downwardly turned flange 18 and the metal of the lower plate is then bent outwardly to

70 form an annular flange 26 adapted to rest upon the edge of the capping 14 around the ice cream receptacle. An annular flange 27 extends upwardly from the flange 26 and interfits with the downwardly turned flange 28

75 which is formed around the outer edge of the upper plate 21. The upper and lower plates of the cover are apertured to provide an opening 30 to permit access to the interior of the ice cream receptacle when the cover is in place. The inner edge of the upper plate 21 is bent downwardly around this

80 opening to form a flange 31 adapted to interfit with an upturned annular flange 32 formed on the lower plate 22. An annular rim or bead 33 is provided on the upper plate 21 around the aperture 30 to prevent contamination of the ice cream by materials accumulating on the upper surface of the cover.

85 The aperture 30 in the cover is closed by a lid 35 comprising two circular plates 36 and 37 of nickel silver or the like which are united around their annular edges, and separated throughout their intermediate areas by a filling 38 of cork or other heat insulating material. The upper sheet 36 of the lid is substantially flat with its outer edge turned down to form an annular flange 39 which terminates above the surface of the cover.

90 The lower plate 37 of the lid is bent upwardly around its outer edges to form an annular grooved part 40 adapted to fit closely the rim or bead 33 carried by the cover. On the outer side of the grooved part 40, the edge of lower plate 37 is bent upwardly

95

100

105

110

as shown at 41 to form an annular spring flange adapted to have a telescoping engagement with the annular flange 39 formed on the upper plate 36.

5 The lid 35 is connected to the cover 20 by a hinge which is mounted on the inner sides of the cover and lid within the ice cream receptacle, thus preventing the possibility of the entrance of heat into the receptacle around parts of the hinge. This hinge comprises a bar 45 provided at one end with two arms 46 terminating at their ends in hubs 47. These hubs are adapted to align with similar hubs 48 formed on the 15 arms 49 of a bracket 50 and the aligning hubs are connected by pins or rivets 51. The arms 49 of the bracket 50 are formed on the plate 52 having a series of apertures 53 therethrough adapted to be engaged by 20 screws 54. These screws pass upwardly through the plate 52 and through the lower plate 22 of the cover and threadedly engage a plate 55 which is mounted on the inside of the cover, as shown in Fig. 1. 25 The other end of the bar 45 of the hinge is provided with two other diverging arms 56 which are provided at their ends with outwardly directed trunnions 57. These trunnions are adapted to form pivotal engagements with the recesses 58 which are formed 30 in a pair of posts 59. These posts are provided with annular flanges 60 adapted to contact with the under side of the lid 35, and with upwardly extending threaded 35 studs 61 adapted to pass through the lower plate 37 of the lid and through a reinforcing plate 62 which is mounted on the inside of the lid as shown in Fig. 2. The studs 61 are engaged by nuts 63 which clamp 40 the post 59 securely to the lid.

The arms 49 of the bracket 50 project inwardly beyond the edge of the aperture 30 in the cover and the arm 45 is of sufficient length to permit the attachment of the posts 45 59 to the lid at points which are disposed with respect to the bracket 50 on the opposite side of the center of the lid. The bar 45 is further provided with a reverse curve in the direction of its length, as shown in Fig. 50 1 so that when the lid 35 is swung upwardly from the cover 20, it will automatically assume a position substantially as illustrated by dotted lines in the drawing where the lid is illustrated as occupying an inclined 55 position parallel to the inner wall 65 of the cabinet 66 which forms a receptacle for fruit juices and other flavors above the outer edge of the cooling box.

This construction provides a convenient 60 and sanitary method of mounting the lid so that it can be readily removed from the cover but is at all times in position to be conveniently closed. The elimination of hinged connections around the edges of the lid and 65 the provision of interfitting contacting sur-

faces on the lid and cover insure a substantially air tight closure which prevents the entrance of heat into the ice cream receptacle and at the same time an unobstructed circular aperture is provided for the attendant in serving ice cream from the container in the receptacle. 70

Although I have shown and described one form of the invention for purposes of illustration, it will be understood that it may be 75 constructed in various other embodiments without departing from the scope of the appended claims.

I claim:

1. In apparatus of the class described, a 80 cooler box cover having an opening therein, a lid normally closing said opening and bodily removable therefrom, and a hinge connected to the inner side of said cover and to the inner side of said lid for permitting the opening movement of said lid and for supporting said lid in an inclined open position, the connection of said hinge on said lid being above its center of gravity when it is in open position. 85

2. In apparatus of the class described, a 90 cooler box having a top capping with an opening therein, a receptacle beneath said opening, a cover for said opening having a central aperture therein, a lid for closing 95 said aperture, a member extending upwardly from said top capping adjacent said opening, and a hinge device pivotally connected to the inner side of said cover and to the inner side of said lid for supporting said lid in an inclined position against said member on said capping when said lid is in open position. 100

3. In apparatus of the class described, a 105 cover having an opening therein, a lid adapted to close said opening, a bracket attached to said cover, a bar pivotally connected to said bracket, and a post secured to an intermediate part of said lid and pivotally engaging said bar, said lid being 110 adapted to be retained automatically by said post in its open position against gravity when swung upwardly away from said cover. 115

4. In apparatus of the class described, 120 a cover having an opening therein, a lid adapted to close said opening, a bracket secured to the inner side of said cover and having a pair of arms projecting beyond the edge of said opening, a bar pivotally connected to said arms, and means for pivotally connecting the other end of said bar to an intermediate part of the under side of said lid, said bar being provided with a reverse 125 curve in the direction of its length and being connected to said lid at a point disposed on the opposite side of the center of said lid from said bracket. 130

5. In apparatus of the class described, a 135 cooler box having a receptacle, a top cap-

ping for said cooler box having a flat upper surface, a cover for said receptacle mounted on said capping and having a central opening therein, said cover having a flat upper surface, a lid having a flat upper surface and arranged normally to close said opening, and a hinge device pivotally connected to the inner side of said cover and to the inner side of said lid for permitting 5
10 said lid to be removed bodily from said opening and to be supported by said hinged device with its edge resting on said capping.

6. In apparatus of the class described, a cooler box having a flat horizontal top capping provided with an aperture, a receptacle mounted beneath said aperture, a cover for said receptacle, said cover having a flat upper surface with an opening therethrough, 15
20 and a bead formed on said upper surface of said cover around said opening.

7. In apparatus of the class described, a cover having an opening therethrough, and a lid adapted to close said opening, said lid

and said cover each comprising upper and lower metallic plates having telescoping engagement with each other around their lateral edges and having heat insulating material interposed between them, said cover being provided with an annular upwardly extending bead around said opening, said lid being provided with an annular depression on its under side adapted to be engaged by said bead. 25
30

8. A cooler cabinet having a receptacle provided with a top opening, a removable circular cover for closing said opening, said cabinet and said cover having flat top surfaces, said cover having a central circular opening therein, a lid for closing said opening in said cover, said lid being removable bodily upwardly from said cover, and a supporting hinge member pivoted on the inner side of said cover and on the inner side of said lid for supporting said lid 40
45 against gravity when said lid is moved upwardly away from said cover.

TULLY DE STEFANI.
